FIG. - 1

FIG. - 2

AMYUIT L. WILSON

Inventor

By Attorney *M. Straw*

UNITED STATES PATENT OFFICE

AMYUIT L. WILSON, OF ELIZABETH, NEW JERSEY, ASSIGNOR TO STANDARD OIL DEVELOPMENT COMPANY, A CORPORATION OF DELAWARE

STEAM BOILER

Application filed February 24, 1926. Serial No. 90,242.

This invention relates to improvements in the construction of steam boilers of the water-tube type. The invention will be fully understood from the following description, taken in connection with the accompanying drawings, in which

Fig. 1 is a side elevation of a boiler installation in accordance with the invention; and

10 Fig. 2 is a top plan view of the device of Fig. 1.

Referring to the drawings, reference numeral 1 denotes a furnace setting of any suitable type, which may be heated for example 15 by a fire maintained on grate 2. As in prior boiler constructions, the first two tubular heating units are arranged in an inclined position in the path of the hot gases from the grate 2 or other heating means. Each of these 20 units comprises respectively a lower drum 3, 3' and an upper drum 4, 4', the lower and upper drums being connected by tubes 5. The individual drums of each pair of drums 3, 3', 4, 4' are connected by nipples 6. A boiler 25 comprising three complete sets of units is shown by way of illustration (see Fig. 2), but any desired number of sets may be used. Since all the sets are alike, description of one will suffice.

30 A steam drum 7 having a steam outlet pipe 8 is arranged in the upper portion of the furnace setting 1 and is in communication with the upper drums 4, 4' through pipes 9 and 10. Three other tubular heaters are shown 35 arranged in the rear portion of the furnace setting. These heaters comprise respectively upper drums 11, 12, and 13 and lower drums 14, 15 and 16. Tubes 17 connect the upper and lower drums of each heater. A pipe 18 40 for supplying feed water to the boiler opens into the lower drum 16. A pipe 19 connects the upper drum 13 with the upper drum 12. The gas or vapor that may tend to accumulate in the upper portion of drum 13 passes off 45 with the water through pipe 19. In this way "gas-binding" is prevented. A nipple 20 connects the lower drum 15 with the lower drum 14. The steam drum 7 is in communication with the upper drum 11 through pipes 21. 50 Connections 19' and 19'', normally above the

water level in this form of the invention, serve to vent gas into the steam drum.

The furnace setting is provided with a vertical baffle plate 22 between the intermediate pair of tubular heaters 17 and with a vertical baffle wall 22' between the intermediate heaters and the last heater. A door 22'' is arranged in the baffle wall. This door is used for cleaning and is kept closed during the operation of the boiler. Horizontal baffles 23 and 23' are arranged to compel flow of gases around the last heater 17. The arrangement of these vertical and horizontal baffles is important, as by it I am able to secure the maximum countercurrent flow of gases and water. The gases pass through a port 24 to the flue not shown.

In accordance with my invention, the water circulation is caused to take place primarily in the tubular heaters 5, or steaming section of the boiler. I have found that by far the greater portion of the heat transfer to the water is accomplished in the steaming section. In this section practically all the vaporization of the water takes place. The heat required for vaporization is approximately ten times that required for bringing the water up to the steaming temperature, and the relative importance of the steaming section with reference to heat input will therefore be apparent. By circulating the water positively and continuously through separate banks of tubes the steaming section only, as shown by the arrows in Fig. 1, a very efficient utilization of the heat of the combustion gases is obtained. In this connection I utilize the principle that the most effective heat transfer is obtained when the temperature differential between the hot gases and the water is greatest, as will be more fully referred to later.

I have found that by proceeding in this way the boiler efficiency is much higher than when the circulation of the water is maintained up through the tubular steaming section 5 and down through heaters 17 and so on continuously, as in prior practice. According to this invention, all three of the heaters 17 are merely a heat exchange or economizer section adapted to raise the temperature of

the water as much as possible before it enters the primary circulating system comprising steaming section 5 and the steam drum 7. The water introduced through pipe 18 flows upwardly through the first heater 17, downwardly through the second heater 17, upwardly through the third heater 17 and into the steam drum 7. From this drum it passes into the steaming section 5. The flow of 10 the water and steam or gas produced from the water is indicated throughout by short arrows, and the flow of combustion gases by long arrows.

In order to obtain the advantages of high 15 temperature differential between the gases and the water to be heated, in all cases I introduce the feed water in countercurrent flow to the gases. The water is then circulated continuously through the tubular steaming 20 section 5 and steam drum 7, as described above. There is accordingly a high temperature differential between the hot gases and the water in the economizer section, since the latter is not heated by circulating water from 25 the steaming section proper, as has been customary in prior practice. The feed water at approximately its boiling point is brought into the steaming section of the boiler, and the introduction of water at relatively low 30 temperature into this section is avoided. A much higher boiler efficiency is attained in this way. More work per unit of heating area is obtained, or a smaller installation will suffice to produce a given amount of horsepower, when the improvements described 35 herein are adopted.

I claim:

1. In a steam generator, a furnace setting 40 having a chamber through which hot gases are adapted to flow from a source of combustion, a steam and water container, an economizer in the chamber connected to said container and through which feed water can be passed to the container, a steaming section 45 in the chamber intermediate the source of combustion and economizer, the section comprising units inclined to the horizontal adapted to contain fluid and having fluid communication at their upper and lower portions respectively, the units being disposed in 50 succession in the path of the gases, the container having fluid communication with the upper portion only of one only of the units.

2. In a steam generator, a furnace setting 55 having a chamber through which hot gases are adapted to flow from a source of combustion, a steam and water container, an economizer in the chamber connected to said container and through which feed water can be 60 passed to the container, a steaming section in the chamber intermediate the source of combustion and economizer, the major portion of the steaming section being exposed to the radiant heat from the source of combustion, the section comprising units inclined 65

to the horizontal adapted to contain fluid and having fluid communication at the upper and lower portions respectively, the units being disposed in succession in the path of the gases, the container having fluid communication with the upper portion only of one only of the units.

3. In a steam generator, a furnace setting 70 having a chamber through which hot gases are adapted to flow from a source of combustion, a steam and water container, an economizer in the chamber connected to said container and through which feed water can be passed to the container, a steaming section 75 in the chamber intermediate the source of combustion and economizer, the section comprising units inclined to the horizontal adapted to contain fluid and having fluid communication at the upper and lower portions respectively, the units being disposed in succession in the path of the gases, the container having fluid communication with the upper portion only of the unit which is farthest from the source of combustion.
